(73) Assignee: **Hunter Douglas Inc.**, Upper Saddle
River, NJ (US)

(57) **CLAIM**

(**) Term: **14 Years**

I claim the ornamental design for a connector for lift cords
and tilt rod of architectural coverings, as shown.

DESCRIPTION

(21) Appl. No.: **29/115,488**
(22) Filed: **Dec. 15, 1999**
(51) LOC (7) Cl. **06-10**
(52) U.S. Cl. **D6/580**
(58) Field of Search D6/575, 577, 580;
160/177, 176.1, 173 R, 174, 168.1, 178.1

(56) **References Cited**

FIG. 1 is an isometric view looking downwardly on the
connector of the present invention.

FIG. 2 is an isometric looking upwardly at the connector.

FIG. 3 is a front elevation.

FIG. 4 is a bottom plan view.

FIG. 5 is a right side elevation.

FIG. 6 is a top plan view; and,

FIG. 7 is a left side elevation.
